BLINKER SIGNALING DEVICE

Sam Gold, Chicago, Ill., assignor to Einson-Free-
man Co., Inc., Long Island City, N. Y., a cor-
poration of Delaware

Application January 15, 1944, Serial No. 518,354

8 Claims. (Cl. 35—14)

My present invention relates generally to signaling devices, and has particular reference to a device of the "blinker" type.

A general object of my invention is to provide certain improvements in a signaling device of the character set forth in the co-pending patent application of Burgoyne A. Diller, Serial No. 515,121, filed December 21, 1943, and in the co-pending patent applications of John V. Horr, Serial Nos. 500,155 and 502,618, filed respectively on August 26, 1943, and September 16, 1943.

The device in question is of simplified structure intended to be manufactured almost entirely of simple inexpensive sheet material such as cardboard or the like. The device is of such a character that it may assume an unusually small and compact form adapted to be held in and operated by one hand of a user.

The type of device to which my invention relates has been designed primarily for instructional purposes, it being intended that large quantities of the device may be manufactured speedily and at low cost, for distribution to trainees in the armed forces, and others, to enhance the teaching of signalling generally and the art of "blinker" signaling in particular. Because of its small and inexpensive nature, the device may also find utility as an educational toy. Nevertheless, since it is a complete signaling device by means of which messages and signals may be transmitted from one person to another, and since certain features of the invention are not necessarily restricted to a device of reduced size, it will be understood that certain phases of the invention may be considered to relate to signaling devices generally.

The structure consists essentially of a pair of superposed front and back signaling members, the front member having a series of adjacent spaced apertures therein and the back member presenting light and dark areas for alternate registry with said apertures during relative sliding movements of said members. The apertures preferably assume the form of parallel slits arranged in a group which defines a sort of circular "spot," and the markings on the back member are correspondingly shaped and arranged. Thus, if the outer surface of the front member is of dark character, the contemplated relative movements of the members will result in making this "spot" alternately dark and light, whereby code messages may be transmitted to an observer at a distance in much the same manner as such messages are transmitted by large-size blinker signaling devices. However, whereas the conventional large-size blinker devices usually employ a beam of light from an artificial source, and require pivoted movements of louvres or the like and all the mechanism and accessories which such an action calls for, the present device is essentially

composed of only the two front and back members referred to.

The relatively slidable front and back members of the present device are associated with a means of resilient yieldable character for urging the members into one condition of registry, whereby signaling may be effected by intermittently forcing or pressing the members into the other condition of registry against the action of the resilient means.

In the aforesaid application of John V. Horr, Serial No. 500,155, an invention is disclosed whose more particular object lies in the provision of a device in which all of the parts may be formed of integral portions of a single blank of sheet material such as cardboard or the like, and in which the contemplated resilient effect may be achieved either without the employment of any extraneous elements or material whatsoever, or merely by means of a simple spring reinforcement of unusually simple and non-critical material.

In the aforesaid application of John V. Horr, Serial No. 502,618, an invention is disclosed whose more particular object lies in the provision of a device in which the basic blank of material is so formed that a printing operation on only one surface thereof will be sufficient to provide all the markings and colorations which the resultant structure requires, and in which only a single gluing operation is required to transform the original blank into the finished product.

It is a more particular object of the present improvement to provide a device which may not only be formed of a single blank of sheet material, and which requires a printing operation on only one surface thereof, but which is of such further simplified structural nature that a lesser amount of sheet material may be employed and no gluing operations whatsoever are required to transform the original blank into the finished product.

I achieve the foregoing objects and advantages, and such other objects and advantages as may hereinafter appear or be pointed out, in the manner illustratively exemplified in the accompanying drawing, in which:

Figure 1 is a perspective view of a signaling device constructed in accordance with the present invention, viewed from the front;

Figure 2 is a similar view from the rear;

Figure 3 is a plan view of the single blank of material of which the present device may be composed;

Figure 4 is a perspective view of one of the initial steps in transforming the blank of Figure 3 into the finished product;

Figure 5 is a cross-sectional view taken substantially along the line 5—5 of Figure 1; and

Figure 6 is a view similar to Figure 5 showing the relationship of the parts when pressure is

exerted upon the device during the signaling operation.

Referring first to Figure 3, it will be observed that the device may be composed in its entirety of a single blank of sheet material which is of elongated substantially rectangular configuration. This blank is divided by the transverse parallel hinge lines 10, 11 and 12 into the successive sections or elements 13, 14, 15 and 16, each of which is substantially rectangular and ultimately forms one of a series of superposed flat elements which cooperatively define the blinker device shown in Figures 1 and 2.

It will be observed that the sections 14, 15 and 16 are of substantially the same width, while 15 the section 13 is of slightly reduced width. The section 15 ultimately defines the front signaling member, and is provided with a series of spaced adjacent apertures 17 which I have illustratively shown in the form of parallel slits conjointly defining a sort of circular "spot." In order that the general nature and capabilities of my invention may be more fully appreciated, it may be mentioned that a satisfactory and highly efficient device may be constructed with this section square in shape, or substantially so, and no more than about two inches long.

The section 13 defines the rear or back member of the two signaling members, and is provided on its front surface with spaced light and dark areas 18. Where the apertures 17 assume the form of slits as shown, the markings 18 on the back member 13 are of corresponding striped configuration, and they are so arranged that reciprocating endwise movements of one of the signaling elements relative to the other will alternately bring the light areas or the dark areas into registry with the apertures or slits 17.

In the preferred construction, the outer face of the front signaling member 15 is printed or marked so as to be of relatively dark character, and the markings 18 on the back member 13 are so arranged that under normal circumstances the dark regions will register with and show through the apertures or slits 17. It may be desirable, but is not necessary, that each of the remaining sections 14 and 16 be also of dark coloration, or one or both of these sections may have certain indicia or informational material printed thereon. In any case, the present structure is so designed that the printing or marking may all be accomplished on a single surface of the blank. The printed or marked surface is shown uppermost in Figure 3. The under surface may be and is preferably left completely unmarked.

The section 14 forms a springy panel which lies behind the back member 13 and serves, in the illustrated embodiment of the invention, to urge the front and back signaling members into such a relationship that the dark areas 18 show through the slits 17.

In connection with the springy panel 14, it is to be observed that it is hinged along the edge 10 to the back member 13, and along the opposite edge 11 to the front member 15. It should also be noted that the length of the springy panel 14, between the hinges 10 and 11, is slightly greater than the length of the back member 13 between the hinge 10 and the free edge 19. The purpose of this relationship of parts is more fully explained hereinafter.

In the present improved structure, the back member 13 and the springy panel 14 are cut back along their adjacent edges, as indicated at 20, so that the hinged region ultimately defines a

projecting finger grip which is designated by the reference numeral 21 in Figures 1, 2, 4 and 5.

The section 16 ultimately defines a means which holds the parts in proper superposed relationship. This section is in effect a retaining flap which is hinged to the front member 15 along the edge 12, this edge being opposite to the edge 11 to which the springy panel 14 is hinged. In the retaining flap hinge 12 there is a recess or slot 22 through which the finger grip 21 ultimately projects.

For a purpose presently to be described, a slit 23 is formed in the panel 14, preferably semi-circular in shape, and a tongue 24 is formed on the end of the retaining flap 16. Also, a transverse score line 25 is preferably provided in the flap 16 in reasonably close proximity to the tongue 24.

After the single blank of Figure 3 has been 20 cut and shaped as indicated, and after its upper surface has been suitably printed, colored, or otherwise embellished or marked, the formation of the blank into the finished product is a relatively simple procedure. The blank is merely 25 folded along the lines 10, 11 and 12, as indicated in Figure 4, so as to bring the back member 13 directly behind the front member 15 with its embellished or printed face directed upwardly, i. e., toward the slits or apertures 17. Ultimately, the 30 retaining flap 16 folds rearwardly over and around the finger grip 21 and assumes a position behind the springy panel 14. For holding together the retaining flap 16 and the springy panel 14 while nevertheless allowing relative 35 movement between them, the tongue 24 is fitted loosely into the slit 23 as indicated most clearly in Figure 2. The device is then ready for use.

To operate the signaling device, it is grasped between the fingers of the user's hand so that he 40 is enabled to press the edge portions 10 and 11 of the springy panel 14 toward each other. When this is accomplished, the rear signaling member 13 is shifted so as to bring the lighter areas 18 into a position in which they show through the slits 45 17. This makes a sort of circular "spot" visible, and the alternate appearance and disappearance of this spot may be employed to transmit the desired signals. The adjustment of the parts in the manner described is indicated in Figure 6, 50 and is accompanied by a resilient outward buckling of the springy panel 14, during which time the retaining flap 16 assumes the angular position shown; the tongue 24 riding freely in the slit 23 but retaining its engagement therewith. The 55 score line 25 assists in keeping the tongue 24 and the slit 23 in permanent interengagement.

When the pressure is released, the springiness of the panel 14 causes it to resume the normal position shown in Figure 5, and this restores the parts into the normal condition. During each 60 operation of the device, the abutment of the edge 19 against the hinge 11, as shown in Figure 6, limits the extent of movement of the back member relative to the front member.

The springiness of the panel 14 may be enhanced by associating with it an additional spring element (not shown) preferably in the form of a simple leaf or strip of resilient material, but the use of such an extraneous element is not absolutely essential, and for the sake of simplicity its employment may usually be and is preferably dispensed with.

It will be observed that the signaling device is thus of unusually simple structural nature. It involves no mechanism which might get out of

order. The springy effect may be achieved without the use of any metal or rubber springs or the like. The resilient action of the springy panel is simple, efficient, and reliable, and serves also as a guide for the reciprocative movements of the rear signaling member, effectively maintaining this member in proper alignment at all times. Of primary advantage is the fact that the entire device may be composed of a relatively small and simple single piece of flat sheet material, which need be marked or printed on only one surface thereof, and that the entire structure may be held together as a unit without requiring any gluing or similar fastening operation whatsoever.

While in the preferred construction, the light and dark areas 18 on the front surface of the member 13 are provided by merely printing or otherwise applying suitable pigment to this surface (e. g., by printing with black ink upon a white background or with white ink upon a darker background), it will be understood that the desired effect could be achieved in various other ways, if desired. For example, the member 16 might have a mirrored surface upon which the suitable areas are provided by blackening or darkening certain predetermined regions, but in such a case it has been found that the desired signaling effect is not of uniform character since the mirrored surface would appear light only in certain angular positions with respect to an exterior source of light to be reflected by it. In any case, the term "light and dark areas" as used herein and in the appended claims is intended to include within its scope any means equivalent to that shown whereby the desired variations in the appearance of the "spot" may be effected by simple reciprocating movements of the character described.

In general, it will be understood that the details herein described and illustrated to explain the general nature of the invention may be modified by those skilled in the art without departing from the spirit and scope of the invention as expressed in the appended claims.

Having thus described my invention and illustrated its use, what I claim as new and desire to secure by Letters Patent is:

1. In a blinker signaling device, a pair of superposed relatively slidable flat front and back members, the front member having a series of adjacent spaced apertures therein, the back member being provided on its front surface with spaced light and dark areas so arranged that relative endwise movements of said members will bring either the light or the dark areas into matching registry with said apertures, and a springy panel lying behind said back member and having one edge hinged to the back member and the opposite edge hinged to the front member, the length of the springy panel between said hinges being greater than the length of the back member between its hinge and its free edge, whereby said panel will normally urge said members into one of said conditions of registry and will buckle rearwardly when pressure is exerted upon its opposite edges to shift the front and back members relative to each other.

2. In a blinker signaling device, the combination with the parts set forth in claim 1 of a means carried by the front member and extending behind said springy panel to hold the parts in superposed relationship.

3. In a blinker signaling device, the combination with the parts set forth in claim 1 of a means

carried by the front member and extending behind said springy panel to hold the parts in superposed relationship, said means comprising a retaining flap hinged to the front member along the edge opposite to that to which the springy panel is hinged.

4. In a blinker signaling device, the combination with the parts set forth in claim 1 of a retaining flap carried by the front member and extending behind said springy panel to hold the parts in superposed relationship, and means for holding together said retaining flap and springy panel while nevertheless allowing relative movement between them.

5. In a blinker signaling device, the combination with the parts set forth in claim 1 of a retaining flap carried by the front member and extending behind said springy panel to hold the parts in superposed relationship, and means for holding together said retaining flap and springy panel while nevertheless allowing relative movement between them, said last-named means comprising a tongue-and-slit engagement.

6. In a blinker signaling device, a pair of superposed relatively slidable flat front and back members, the front member having a series of adjacent spaced apertures therein, the back member being provided on its front surface with spaced light and dark areas so arranged that relative endwise movements of said members will bring either the light or the dark areas into matching registry with said apertures, a springy panel lying behind said back member and having one edge hinged to the back member and the opposite edge hinged to the front member, said panel normally urging said members into one of said conditions of registry, said back member and springy panel being cut back along their adjacent edges so that the hinged region defines a projecting finger grip, and means carried by the front member and extending behind said springy panel and around said finger grip to hold the parts in superposed relationship.

7. In a blinker signaling device, a pair of superposed relatively slidable flat front and back members, the front member having a series of adjacent spaced apertures therein, the back member being provided on its front surface with spaced light and dark areas so arranged that relative endwise movements of said members will bring either the light or the dark areas into matching registry with said apertures, a springy panel lying behind said back member and having one edge hinged to the back member and the opposite edge hinged to the front member, said panel normally urging said members into one of said conditions of registry, said back member and springy panel being cut back along their adjacent edges so that the hinged region defines a projecting finger grip, and means carried by the front member and extending behind said springy panel and around said finger grip to hold the parts in superposed relationship, said means comprising a retaining flap hinged to the front member along the edge opposite to that to which the springy panel is hinged, there being a recess in the retaining flap hinge through which said finger grip projects.

8. In a blinker signaling device, the combination of parts set forth in claim 7, said front and back members, said springy panel, and said retaining flap being integral hingedly-connected parts of a single blank of cardboard.

SAM GOLD.
